UNITED STATES PATENT OFFICE

108,892

DESIGN FOR A GRILLE-WORK TRUCK

Alexis de Sakhnoffsky, Philadelphia, Pa., assignor to The White Motor Company, Cleveland, Ohio

Application January 21, 1937, Serial No. 67,187

Term of patent 7 years

To all whom it may concern:

Be it known that I, Alexis de Sakhnoffsky, a subject of the Czarist Regime of Russia, residing at city of Philadelphia, in the county of Philadelphia, and State of Pennsylvania, have invented a new, original, and ornamental Design for Grille-Work Truck, of which the following is a specification, reference being had to the accompanying drawing forming part thereof.

Fig. 1 is a side elevation of a grille-work truck of my design.

Fig. 2 is a rear elevation thereof.

Fig. 3 is a front elevation thereof.

Fig. 4 is a fragmentary perspective view of the front end portion of the truck.

The portions shown in solid lines portray the dominant features of applicant's design.

I claim:

The ornamental design for a grille-work truck, as shown and described.

ALEXIS DE SAKHNOFFSKY.
